To all whom it may concern:

Be it known that I, ADELAIDE J. FELT SHARER, a citizen of the United States, residing in Cleveland, in the county of Cuyahoga and State of Ohio, have invented a new, original, and ornamental Design for Brooches, Buttons, Badges, Stick-Pins, Signs, Emblems, Flags, Pennants, and Articles of a Similar Nature, of which the following is a specification, reference being had to the accompanying drawing, forming part thereof.

The figure is an elevation of a brooch, showing my new design.

My design, it will be noted, is a gilt bordered white shield upon the face of which is displayed a red "W" over a blue "M," both being edged or bordered, whereby the national colors are used in effective display and a pleasing and striking design produced.
